UNITED STATES PATENT OFFICE

ALBERT A. CRIPPS, OF DETROIT, MICHIGAN, ASSIGNOR, BY MESNE ASSIGNMENTS, TO CHRYSLER CORPORATION, A CORPORATION OF DELAWARE

BODY CONSTRUCTION

Application filed July 2, 1928. Serial No. 289,889.

This invention relates generally to the framework of motor vehicles and the like and refers more particularly to the sill frame assembly thereof whereby the body sill and chassis frame are combined into one unit or 5 sill.

One of the essential objects of the invention is to provide a body structure in which one set of sill frame members is substituted for the usual body sill and chassis frame members.

Another object is to provide sectional sill members wherein the respective sections of each sill reinforce and strengthen each other 15 and in which one section of each sill member constitutes a direct means of attachment for the body framework.

A further object is to provide an arrangement wherein one of the sill frame sections 20 also constitutes an apron for the vehicle.

With the above and other objects in view, the invention consists in certain novel features of construction, combinations and arrangements of parts as will be more fully 25 described and particularly pointed out in the appended claims.

In the drawings:

Figure 1 is a side elevation of the composite body construction made in accordance 30 with the present invention;

Figure 2 is a side elevation of a center pillar and its connection to the vehicle frame;

Figure 3 is a section taken on line 3—3 of Figure 2;

Figure 4 is a section taken on line 4—4 of Figure 3;

Figure 5 is a side elevation of the lower portion of the cowl and its connection to the vehicle frame;

Figure 6 is a section taken on line 6—6 of Figure 5;

Figure 7 is a section taken on line 7—7 of Figure 5;

Figure 8 is a side elevation of the rear quarter section of the body;

Figure 9 is a section taken on line 9—9 of Figure 8;

Figure 10 is a section taken on line 10—10 of Figure 8;

Figure 11 is a section taken on line 11—11 of Figure 8.

Referring now to the drawings and particularly to Figure 1, the numeral 1 designates generally the side of a motor vehicle construction comprising a main side frame member 2 substantially channel-shape in cross section, and an auxiliary sill 3 substantially inverted L-shaped in cross section secured to the lower portion of the body and in turn securing the body to the main frame member.

Figures 2 to 4 represent portions of the body construction intermediate the ends of the vehicle, the vehicle in the present instance being of the closed body type. As shown, the frame member 2 is relatively thin in cross section and besides performing the functions of a main sill, it also constitutes an apron having its lower portion exposed to view and finished for this purpose.

The auxiliary sill is relatively thick in cross section as compared with the main sill and is mounted upon the upper portion of the main sill, a layer of anti-squeak material 4 being interposed between the sills as shown in Figure 3. In this latter figure there is disclosed a central wooden pillar 5 having its rear face provided with a longitudinal pocket 6 for receiving a flat pillar iron 7, the lower end of

which is formed into a yoke 8 having portions 9 and 10 respectively secured to the legs of the auxiliary sill 3. While any suitable fastening means may be employed for securing the iron to the pillar, in the present instance I utilize both wood screws 11 and bolts 12, the bolts passing through the iron and pillar and having their end portions projecting into recesses 13 where they are threadedly engaged by nuts 14. The lower end of the pillar terminates above the portion 10 of the yoke and is adapted to rest upon a finish strip 15, the rear face of which is slotted to receive the portion 10 of the yoke. This strip is secured to the sill 3 by a bolt and nut arrangement

similar to that described above, one of the bolts 16 in this instance passing through the portion 10 of the yoke and forming a secure connection between the auxiliary sill, iron and strip. Any suitable means such as the

100

rivets 17 are provided for securing the portion 9 to the transverse leg of the sill 3. Preferably the pillar and strip are enclosed in metallic casings 18 and 19 respectively 5 which conceal the fastening means from view and also give the desired finish to this portion of the body.

As shown, the frame 2 and sill 3 are bolted together by the fastening means 20 and the 10 horizontal leg 21 of the sill 3 terminates flush with the upper edge of the main sill or frame member 2. Preferably a floor board supporting member 22 extends longitudinally of the two sills and has an edge portion 15 thereof clamped between the leg 21 and the upper edge of the main sill.

Referring now to Figures 5 to 7 there is disclosed the means for securing the lower end of the cowl 31 to the forward portion 20 of the sills 2 and 3. As in the other views, the upper part of the main sill or frame member is secured to the auxiliary sill and is separated therefrom by the anti-squeak material 4. The cowl comprises spaced inner 25 and outer panels 23 and 24 respectively, the outer panel terminating substantially flush with the lower end of the sill 3, while the inner panel abuts the outer face of said sill and is provided at its lower end with an open 30 return bent portion 25 receiving and embracing the lower edge of the outer panel. In Figure 6, a bolt 26 is shown extending entirely through the panels 23, 24 and the sills 2 and 3 and engaging a nut 27 for securely 35 clamping all of these elements together. Figure 7 is a section taken at a different point from that of Figure 6 and is somewhat similar thereto except that the fastening means constitutes a rivet 28 which merely secures 40 the panels 23 and 24 to the auxiliary sill 3.

Referring to Figures 8 to 11, there is illustrated the rear quarter section of the vehicle body. In these views the rear end of the sill 3 and a rear auxiliary sill 29 are shown 45 in overlapping engagement, the sill 29 also being L-shaped in cross section and having each of its legs riveted to the legs of the sill 3. The sill 29 is curved upwardly and rearwardly as shown in Figure 8 and supports a 50 relatively thick sheet metal member 30, this member being curved outwardly to constitute a portion of a wheel housing and fender support and having a lower inturned flange 31 resting upon and riveted to the sill 29.

The upper portion of the member 30 is 55 formed into a strap 32 which is secured to the lower portion of a rear pillar 33, this pillar terminating above the sills 2 and 29 and merging into a curved pillar section 34. The strap 32 is also continued and merged into a flange 35 of the member 30 constituting a 60 supporting flange for the curved pillar section 34. Preferably the member 30 is covered by a thin sheet metal panel 36 which is extended rearwardly beyond the member, the

forward end portion of this panel concealing the curved pillar section 34 and constituting a finish strip 37. The lower edge of the panel 36 is flanged as at 38 and is inserted between the sill 29 and flange 31 of the member 30 where it is secured in place by the same rivets 70 which secure these elements together.

While in the present instance my sill assembly is shown in connection with a closed body of the four door sedan type, it will be 75 apparent that it is not limited to this one particular type of body but can be adapted for use with any desired type of body construction and that such changes may be resorted to when desired as fall within the scope of what 80 is claimed.

What I claim as my invention is:

1. In a vehicle framework, the combination with a main sill substantially channel-shaped in cross section, of an auxiliary sill substantially inverted L-shape in cross section secured to said main sill and forming therewith a chassis framework, a pillar, and means for connecting said pillar to the auxiliary sill including a pillar iron secured to the pillar and provided with a yoke at its lower end having portions secured to the legs of said auxiliary sill. 85

2. In a vehicle framework, the combination with a sill substantially inverted L-shape in cross section, a pillar, a pillar iron secured to said pillar and provided with a yoke at its lower end having portions engaging the legs of said sill, and a finish strip extending longitudinally of said sill and engaging portions 90 of said pillar and yoke respectively. 100

3. In a vehicle framework, the combination with a sill substantially inverted L-shape in cross section, a pillar, a pillar iron secured to said pillar and provided with a yoke at its lower end having portions engaging the legs of said sill, a finish strip extending longitudinally of said sill and engaging portions 105 of said pillar and yoke respectively, and fastening means passing through said sill, yoke portion, and finish strip for securing said parts together. 110

In testimony whereof I affix my signature.
ALBERT A. CRIPPS.
